(57) **CLAIM**

The ornamental design for endoscopic treatment device, as
shown and described.

DESCRIPTION

FIG. 1 is a first perspective view of an endoscopic treatment
device according to my new design;

FIG. 2 is a front view thereof;

FIG. 3 is a back view thereof;

FIG. 4 is a plain view thereof;

FIG. 5 is a base view thereof;

FIG. 6 is a left side view thereof;

FIG. 7 is a right side view thereof;

FIG. 8 is a second perspective view thereof; and,

FIG. 9 is a reference drawing showing a state of use thereof.
The present article is attached to a distal portion of a tube of
an endoscopic treatment system to be opened and closed in a
scissor-like motion as shown in the perspective view, FIG. 8.
The present article constitutes the distal portion of the endo-
scopic treatment system and is inserted to the target lesion
through the forceps channel of the endoscope for grasping the
target lesion by scissor-like motion and excising the same by
applying high-frequency current.

Broken lines shown in the drawings illustrate portions of the
endoscopic treatment device and form no part of the claimed
design.
